US0D1099624S

(12) **United States Design Patent** (10) **Patent No.:** **US D1,099,624 S**
(45) **Date of Patent:** **** Oct. 28, 2025**

(54) **DRINKWARE LID**

(71) Applicant: **YETI Coolers, LLC**, Austin, TX (US)

(72) Inventors: **Roy Joseph Seiders**, Austin, TX (US);
Matthew Joseph Petrillo, Austin, TX (US);
Kyle Ellison, Austin, TX (US)

(73) Assignee: **YETI Coolers, LLC**, Austin, TX (US)

(**) Term: **15 Years**

(21) Appl. No.: **29/904,886**

(22) Filed: **Oct. 12, 2023**

Related U.S. Application Data

(63) Continuation of application No. 29/759,502, filed on Nov. 23, 2020, now Pat. No. Des. 1,005,775, which is a continuation of application No. 29/674,592, filed on Dec. 21, 2018, now Pat. No. Des. 902,646, which is a continuation of application No. 29/606,307, filed on Jun. 2, 2017, now Pat. No. Des. 836,395.

(57) **CLAIM**

The ornamental design for a drinkware lid as shown and described.

DESCRIPTION

FIG. 1 is a top, front, right perspective view of a drinkware lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are shown for the purpose of illustrating both parts of the article we well as environmental subject matter of an exemplary container. None of the broken lines form part of the claimed design.

1 Claim, 7 Drawing Sheets
